UNITED STATES PATENT OFFICE.

JOHN O'NEAL, OF TERRE HAUTE, INDIANA.

COLLAR BUTTON.

1,419,298.

Specification of Letters Patent. Patented June 13, 1922.

Application filed February 26, 1921. Serial No. 447,987.

To all whom it may concern:

Be it known that I, JOHN O'NEAL, a citizen of the United States, and a resident of Terre Haute, county of Vigo, and State 5 of Indiana, have invented a certain new and useful Collar Button; and I do hereby declare that the following is a full, clear, and exact description thereof, reference being had to the accompanying drawings, 10 in which like numerals refer to like parts.

This invention relates to a collar button, and the chief object thereof is to provide a button which will detachably secure a collar to a garment in an improved manner, 15 and which will retain said collar in the garment supported position and prevent the accidental detachment of the same.

The chief feature of the invention consists in the particular construction of the 20 collar button.

The full nature of the invention will be understood from the accompanying drawings and the following description and claim.

25 In the drawings, Fig. 1 is a front elevational view of a collar button showing the same applied to a garment. Fig. 2 is a perspective view of the improved collar button. Fig. 3 is a central sectional view 30 of the collar button in securing relation with a garment and a collar.

In the drawings 10 indicates the outer fold and 11 the inner fold of a neck band of a garment, and 12 indicates a button hole in the outer fold of said neck band. 35 The neck band is adapted to be associated with a collar 13 provided with a similar button hole 14 in the base thereof, which button hole is adapted to register with the 40 button hole 12 when said collar is to be secured and is secured to the garment by the neck band.

The collar button by which the collar is secured to a garment in the usual manner 45 comprises a base portion 15 which is arcuate in form and which is continued or extended to form a pair of oppositely extending arcuate wing plates 16 integral with the body portion 15. Preferably integral with 50 the body portion 15 are a plurality of tongue portions, three being herein shown, the two outside tongue portions being designated by the numeral 17 and the intermediate or middle tongue portion being designated by the numeral 18. The tongue

portions 17 are similar, so a description of one will suffice for both. The tongue portion 17 extends outwardly from the arcuate base 15 and then extends downwardly therefrom, the lower free end being bent outwardly at 19, as shown clearly in Figs. 2 and 3. The intermediate or middle tongue portion 18 extends outwardly from the base 15 and provides an intermediate portion 20 which spaces the tongue portion 18 65 which also depends from said base portion at a distance from the tongues 17. The lower free end 21 of the tongue portion 18 is bent inwardly as shown. Thus, the lower free ends 19 and 21 cooperate together as 70 shown clearly in Fig. 3 to form a clamping connection. It is to be understood that the outwardly turned free end 21 of the middle tongue 18 is readily receivable by the button hole 14 of the collar 13; while the inwardly extending free ends 19 of the outer tongues 17 provide that said tongues 17 do not pass through the button hole 14 but continue in their downward movement between the collar base and the garment when 80 the collar is being applied to the garment. Thus, the tongues 17 are interposed between the collar and the neck band of the garment; while the tongue 18 extends through the button hole of the collar and 85 secures said collar to the neck band.

The wings 16 provide an enlargement or stop means which prevents the non-passage of the base portion 15 through the neck band, button hole 12 while the cooperating 90 tongues 17 and 18 secure the collar 13 to the neck band and prevent the accidental detachment of the same, the free ends of said tongues cooperating to form a clamping engagement for retaining said collar 95 in connection with the collar button. Thus, the collar is adapted to be detachably secured to a garment by the aforesaid collar button in an improved manner, which prevents the accidental detachability of the collar therefrom.

The invention claimed is:

A collar button for attaching a collar to a garment, each having a button hole therein adapted to register, including a base 105 portion non-passable through the garment button hole, and an attaching portion passable therethrough comprising three tongues adapted to lie parallel to said collar in two groups, the two outer tongues lying upon 110

one side of said collar and the middle tongue lying upon the other side of said collar, one of said tongue groups being passable through the collar button hole 5 when in registering relation, the ends of said tongues terminating adjacent each other and the tongues of each group having their

ends extending in opposite directions from the ends of the tongues of the other group for clamping engagement.

10

In witness whereof, I have hereunto affixed my signature.

JOHN O'NEAL.
